ABDOMINAL BELT

Philomène Decat Resimont, Liege, Belgium

Application January 10, 1947, Serial No. 721,272
In Belgium October 19, 1942Section 1, Public Law 690, August 8, 1946
Patent expires October 19, 1962

3 Claims. (Cl. 2—41)

1

The present invention has for its object an improved abdominal belt consisting in a front piece and a back piece which are connected together by straps extending from the upper and lower corners of the back piece to be clasped in the upper and lower parts of the front piece, said front and back pieces being provided with lateral cut-out parts at the place where the belt engages the hips, to provide entirely free spaces for the hip point and to permit in consequence a perfect mobility of the body in relation to the thighs, without influencing the position of the front piece.

As the four straps connecting both main parts of the belt are made of supple material and those on the lower side are particularly elastic, the belt will by no means impede the person wearing it, whilst ensuring a perfect and firm support to the lower part of the abdomen and the internal organs of the body at this point. The belt comprises ordinary sub-thigh bands, preferably elastic, and it is provided with stocking-suspenders when intended for a woman.

A preferred embodiment of the invention will be described hereinafter with reference to the accompanying drawing.

Figs. 1 and 2 are front views of the belt, respectively with the lower straps open and with the lower straps closed, the upper straps being closed in both figures.

Fig. 3 is a rear view of the same.

The belt according to the invention comprises a back piece 1 constituted by a central elastic band *a* and two side flaps *b*—*b*. A re-entrant cut-out part *c* is provided at the lower part of the side edges; the belt further comprises a front piece 2 which is applied on the lower part of the abdomen and is also provided with two re-entrant cut-out parts 5 on the side edges. The back piece is reinforced by vertical stays or stiffeners *d* and the front piece by oblique stays or stiffeners *c'*. The upper corners of the front piece 2 are connected to the upper corners of the back piece 1 by straps 4 with buckles 3, and the lower part of the front piece 2 is connected to the lower part of the back piece 1 by straps 6 fastened to the lower corners of said back piece. The straps 6 are constituted by two or more adjacent elastic bands with button-holes 10 which are formed by transverse stitches 9 and pass over buttons 7 fastened by ribbons of small length in the plane of the front piece 2. The ends of the straps 6 are slid under a lap 8 secured on the front face of the piece 2; the latter has an elastic gusset or pocket 15 at its upper

2

edge and in the middle. The sub-thigh bands 11 which are clasped to buckles 11' on the front piece 2 are arranged to encircle the thigh in such a manner that they maintain the same pressure both in the standing and sitting position; to this end the sub-thigh bands have their ends at an angle of about 45° to the median axis of the belt. The abdominal belt intended for women is provided with the usual stocking-suspenders 12.

Referring to Fig. 2, it will be immediately appreciated that in the assembled and closed position of the various parts of the belt, spaces completely free are left laterally, so that the hip points are relieved from any pressure and the body movements are possible without influencing the position of the front piece, which assumes a position slightly lower in relation to the backpiece. Whatever the body position in relation to the legs may be, no distortion will take place in the belt proper and the pressure of the front piece 2 will continuously exert itself perfectly on the organs sustained by the belt.

There are four inner cushions at the upper and lower ends of the front piece to prevent hindering pressures. A renal and/or stomachal pad may be provided.

The particular conformation of the elements 1 and 2 gives rise to a saving of material, whilst producing a useful effect for the person wearing the belt.

According to the invention, each of the stocking-suspenders is fastened by two bands or ribbons arranged at a suitable angle to give a constant pressure both in standing and sitting positions, without the weight of the body being transmitted to the stocking-suspender. This results from the fact that owing to the arrangement of the clasp the effect is exerted at one time on one leg of the V, at another time on the other, which gives a constant tension and makes it uniform.

The back piece 1 is slightly curved at its upper edge to correspond in shape to the curvature of the rear thorax. The stiffeners of the front piece 2 are right or arcuated inwards according to the state of ptosis of the invalid. The belt is put on when the invalid is in the lying position, i. e. when the abdominal and dorsal muscles are entirely relaxed; it is fastened without any displacement of the body, resulting in a maintenance of the organs immediately when the invalid rises, which is not obtained with other belts as they are attached and adjusted at the back. The drawback of the belts known heretofore for

raising up the stomach and the kidneys is that their straps are fastened at the back, with resulting contraction, i. e. displacement of organs, upon their fastening.

Owing to its shape, the back piece gives complete freedom to the gluteal muscles, and bears on the muscles of the dorsal frame, so that the same result is obtained as by the pressure of both hands upwards at the back.

There results from said suitable shapes of the back and front pieces 1 and 2 two supporting movements, that of the front piece upwards and that of the back piece also upwards, said movements bringing immediate relief, with a natural effect, to the invalid and taking place continuously both in the standing and sitting positions.

The belt is upholstered or quilted to give stiffness to the fabric.

I claim:

1. An abdominal belt consisting of a back member and a front member spaced and detachable from each other, four straps each permanently attached at one of its ends to the back member, said straps being attached adjacent the upper and lower ends of the lateral edges of the back member, the straps attached adjacent the upper ends being adapted to extend around the wearer's hips above the hip points and the straps attached adjacent the lower ends being adapted to extend around the wearer's hips below the hip points, and means for adjustably securing the free ends of said straps to adjacent portions of the front member, said four straps being the only connections between said front and back members.

2. An abdominal belt consisting of a back member and a front member spaced and detachable from each other, each member having at its lateral edges re-entrant cut-out portions to receive the hip points of the wearer, four straps each permanently attached at one of its ends to the back member, said straps being attached adjacent the upper and lower ends of the lateral

edges of the back member, the straps attached adjacent the upper ends being adapted to extend around the wearer's hips above the hip points and the straps attached adjacent the lower ends being adapted to extend around the wearer's hips below the hip points, and means for adjustably securing the free ends of said straps to adjacent portions of the front member.

3. An abdominal belt consisting of a back member and a front member spaced and detachable from each other, each member having at its lateral edges re-entrant cut-out portions to receive the hip points of the wearer, four straps each permanently attached at one of its ends to the back member, said straps being attached adjacent the upper and lower ends of the lateral edges of the back member, the straps attached adjacent the upper ends being adapted to extend around the wearer's hips above the hip points and the straps attached adjacent the lower ends being adapted to extend around the wearer's hips below the hip points, and means for adjustably securing the free ends of said straps to adjacent portions of the front member, a pair of bands each permanently attached at one of its ends to the lower edge of the front member at an angle of 45° with respect to the median axis thereof, and means for adjustably attaching the free ends of the bands to said front member.
